WIRE-LAYING DEVICE

Irwin Trevanian Kempe, Longparish, Andover,
EnglandApplication January 13, 1939, Serial No. 250,812
In Great Britain January 25, 1938

6 Claims. (Cl. 242—54)

This invention relates to apparatus for temporarily laying electric cables, such as telephone cables, and it is especially applicable for use in military exercises or operations where telephone cables have to be laid on the ground or supported on hedges or the like, the cable being paid out from and afterwards picked up upon a travelling vehicle. The apparatus according to the present invention is of the kind in which the cable is stored on a rotatable drum and drawn therefrom by a feed-roll device for paying out the cable, as described in my United States Patent applications Serial No. 123,939, filed February 3, 1937, now Patent No. 2,203,435, dated June 4, 1940 and No. 171,519, filed October 28, 1937 now 15 Patent No. 2,223,110, dated November 26, 1940.

The present invention has for its main objects to provide transmission means for rotating the feed roll device by the rotation of the storage drum, or vice versa, to dispense with the provision of a countershaft for driving either of the said devices, as required, while allowing the other of the said devices to be operated by the pull of the cable, to ensure direct relation between the speeds of the said devices, to provide means for utilizing the mass of the drum and coiled cable to ensure steady rotation of said devices and regular movement of the cable, and to compensate automatically for the varying diameter of the coil of cable upon the drum, both as regards the speed-relation necessary for feeding out or winding in the cable without slip and as regards the flywheel effect provided by the rotating drum with its variable quantity of cable.

Other objects and advantages of the present invention will appear from the subsequent description given with reference to the accompanying drawings, in which:

Figs. 1, 2 and 3 are respectively a side elevation, a plan and an end elevation of one form of carrying out the present invention. Fig. 4 is a detail, drawn on a larger scale, showing a free-wheel device incorporated in the driving mechanism.

Figs. 5 and 6 are diagrams showing modified forms of the invention.

In the construction illustrated in Figs. 1-3, the cable storage drum *a* and the feed-roll device *b* are connected by variable speed transmission means in the form of a flat belt *c* engaging the periphery of the coil of cable *d* upon the drum *a* and running over a flanged belt pulley *e* secured upon the spindle *f* of the driven feed-roll *b*, the effective diameter of said belt pulley *e* being substantially equal to that of said feed-roll *b*.

The co-operating pressure roll *b* is arranged to press the cable against the feed-roll *b*, the rolls being preferably of metal, faced with rubber, and the cable is kept in position between these rolls by pairs of guide rolls *b*. The cable drum is 5 detachably mounted upon a squared portion *a* of a rotatable driving spindle *a*, from which it can be removed for replacement when empty or otherwise when desired.

10 As the cable drum *a* is revolved for paying out the cable *d*, the belt *c* which frictionally engages the "pulley face" provided by the coil of cable on the drum will drive the belt pulley *e*, which in turn will rotate the driving feed-roll *b* at a peripheral speed substantially equivalent to that of the coil of cable; the feed-roll device thus draws the free end of the coiled cable onward just as fast as it is unwound from the storage drum, in spite of the decreasing diameter of the 15 coil, the cable being thrown forward in the known way from the feed-roll device.

I provide suitable means, as hereafter described, to compensate for the decreasing effective diameter of the coil of cable *d* when the 20 cable is being paid out by the feed-roll device, so that the belt *c* is kept automatically tensioned and a continuous feed of cable is obtained through the feed-roll device.

The proportional drive between the cable drum 25 *a* and the feed-roll spindle *f* varies exactly and directly with the decreasing diameter of the coil as the cable *d* is drawn off, although it becomes necessary for the drum spindle *a* to revolve at an increasingly higher speed as the coil of cable 30 *d* decreases in size, in order to maintain the same rate of delivery of the cable from the feed-roll device.

Such a variable speed can be imparted to the 35 drum spindle either by power or by hand, employing means such as a flexible power shaft, a motor or a detachable crank handle. As shown in Figs. 1-3, a crank handle *h* is fitted loosely upon the end of the spindle *a* remote from the cable storage drum, the spindle *a* being extended 40 through a gear box *i* to receive the handle, which is retained by a nut *h*. This gearbox comprises a gear-fitted lay shaft *h* adapted to be driven by a gear-wheel *h* fixed to the handle *h* and to drive a pinion *a* loose on the spindle *a* at greatly increased speed relatively to that of the handle *h*.

As seen in Figs. 3 and 4, the pinion *a* is slotted 45 diametrically at one end to provide jaws *a* engaging with a diametrical rib *g* upon a driver plate *g* carrying four pegs *g* which engage in

spaces between the teeth of a free-wheel g^2 screwed tightly upon a hub member g^3 keyed to the spindle a^1 , the free-wheel g^2 being of the ordinary kind used on chain-driven bicycles. The multiplying gear train h^1, h^2, a^2 enables the crank handle h to drive the spindle a^1 and drum a at sufficiently high speed for paying out the cable without excessive or inconvenient speed of the handle, while the provision of the free-wheel g^2 allows the handle to be released if desired, the drum then continuing to rotate by its own inertia, without danger of injury by the handle turning idly with it.

The feed-roll device b is shown mounted at the head of a pillar l slidable on parallel arms kk^1 supported in bosses i^0 upon the gear box i . A spring l^1 , coiled around the arm k , between the pillar and the gearbox, acts on the pillar to move the feed-roll device away from the drum spindle a^1 , and thus keep the belt c in tension.

During the unwinding of the cable d from the drum a , the diameter of the coil of cable decreases, as already mentioned, and the spring l^1 gradually moves the slidable pillar l along the arms kk^1 , thus displacing the feed-roll device b away from the drum so as automatically to take up any slack which would otherwise occur in the driving belt c . Instead of the slidable pillar supporting the feed-roll device, I may provide other means, for example as described hereafter with reference to Fig. 6, tending to displace the feed-roll device b relatively to the drum a and thereby keep the belt tensioned.

The feed-roll device b should be so positioned that the cable d passing between the rolls b^1b^2 and guided by the rolls b^3 is aligned approximately with the middle portion of the coil of cable on the drum, as seen in Figs. 2 and 3, while the endless flat belt c should bear on the coil of cable near one side-cheek a^4 of the drum. In unwinding the cable from its storage drum, the run of the cable leaving the coil travels from one side-cheek of the drum to the other and then back to the first side (assuming the cable to have been evenly wound on the drum), the cable escaping laterally from inside the loop of the endless belt c and the effective diameter of the coil being thereby gradually decreased; if the vehicle from which the cable is laid is to maintain its speed of travel, and the cable is to be fed out at a corresponding speed, the drum must be rotated at increasing speed, inversely proportionate to its decreasing diameter, but the variable transmission provided between the cable storage drum and the feed-roll device will automatically compensate for the decreasing diameter of the coil of cable on the drum in order to maintain the operation of the feed-roll device at substantially constant speed, proportionate to that of the vehicle.

It will be noted that in this form of cable-laying apparatus I employ the cable drum as a flywheel, and that as the weight of the cable thereon decreases, the increasing speed of the drum will maintain the steady or flywheel effect. Where the apparatus is hand-operated, it is therefore not necessary to add a flywheel to give smooth and even rotation of the parts; in this way unnecessary weight is saved.

To facilitate the fitting of the cable drum and its exchange when emptied, in cases where there is not sufficient room for sliding the drum horizontally on and off the driving spindle a^1 , I may provide the gearbox i with a pivotal mounting whereby the spindle a^1 projecting from the gear-

box may be tilted upwardly from the horizontal. The gearbox is shown formed with a base flange j , which is mounted upon a pivot bolt j^1 , carried by a support j^0 adapted for bolting to a bracket j^1 (Fig. 1) upon the vehicle; the support j^0 is provided with a displaceable locking bolt j^2 fitted with a nut j^3 whereby the base flange j can be secured to its support in normal working position. When the nut j^3 is disengaged and the gearbox is tilted up about its pivot j^1 , the drum can be lifted off its spindle after removal of a retaining nut a^8 .

When it is desired to recover the laid cable by winding it back on to the drum a , the belt c can, if desired, be retained in operation so as to drive the feed-roll device in the opposite direction by reversing the direction of rotation of the drum. Alternatively, the belt c can be removed from the pulley e on the feed-roll spindle, the cable in that case being either guided and returned between the rolls $b^1b^2b^3$, or taken clear of the rolls and guided by hand on to the drum. If the handle h and free-wheel g^2 have been employed for paying out the cable from the drum, the laid cable may be recovered by slipping the drum off its spindle a^1 and replacing it in the reverse position, when continued turning of the handle with the free-wheel driving in the same direction will rewind the cable; if preferred, however, I may utilize the other end of the spindle a^1 or the exposed side-cheek a^4 of the drum for turning the latter backwards when it is desired to recover the cable.

In the arrangement indicated in Fig. 5, the feed-roll device b is shown provided with a second belt-pulley m whereby the spindle of the roll b^1 can be power-driven through a belt from any suitable source of power, the same spindle operating to drive the drum a by means of its pulley e and the flat belt c , with variable speed-relation as above described.

In the modification of Fig. 6, the belt c is automatically tensioned by mounting the drum spindle a^1 on a tilting lever n pivoted at n^1 upon a convenient support, such as the bracket j^1 shown in Fig. 1. The lever n is inclined beyond the vertical, away from the feed-roll device, so that the weight of the storage drum and cable will automatically keep the belt c tensioned whatever the effective diameter of the coiled cable, the inclination increasing to compensate the reduction of weight as the cable is unwound off the drum.

What I claim is:

1. A transportable cable-laying and recovery device, comprising a rotatable cable-storage drum, coacting rolls for feeding out cable unwound from said drum, a belt pulley connected to one of said rolls, a belt engaged by said pulley and mounted partly around the coil of cable upon said drum, and means for rotating said drum and said roll simultaneously through the agency of said belt and pulley, the speed-relation of said drum and said roll varying with the diameter of said coil.

2. A transportable cable-laying and recovery device, comprising a rotatable cable-storage drum, coacting rolls for feeding out cable unwound from said drum, a belt pulley connected to one of said rolls, a belt engaged by said pulley and mounted partly around the coil of cable upon said drum, and means for rotating said drum in a direction to unwind cable from said coil, said cable-feeding rolls being rotated by said belt and

pulley at a speed and in a direction to pay out the cable as it is unwound from said coil.

3. A transportable cable-laying and recovery device, comprising a rotatable cable-storage drum, coacting rolls for feeding out cable unwound from said drum, a belt pulley connected to one of said rolls, a belt engaged by said pulley and mounted partly around the coil of cable upon said drum, and means for rotating said rolls, the coil of cable on said drum being rotated by said pulley and belt at a peripheral speed substantially equivalent to that of said rolls.

4. A transportable cable-laying and recovery device, comprising a rotatable cable-storage drum, coacting rolls for feeding out cable unwound from said drum, a belt pulley connected to one of said rolls, a belt engaged by said pulley and mounted partly around the coil of cable upon said drum, said drum and said pulley being relatively displaceable to maintain tension of said belt during the unwinding of cable from said coil, and means for rotating either of said drum and said roll, the other of said drum and said roll being rotated simultaneously through the agency of said belt and pulley, and the speed-relation of said drum and said roll varying with the diameter of said coil having said belt mounted partly therearound.

5. A transportable cable-laying and recovery device, comprising a rotatable cable-storage drum, coacting rolls for feeding out cable unwound from said drum, a belt pulley connected

to one of said rolls, a belt engaged by said pulley and mounted partly around the coil of cable upon said drum, a support for said rolls and belt pulley, said support being slideable towards and away from said drum to maintain tension of said belt, spring means urging said support to slide away from said drum and means for rotating either of said drum and said roll, the other of said drum and said roll being rotated simultaneously through the agency of said belt and pulley, and the speed-relation of said drum and said roll varying with the diameter of said coil having said belt mounted partly therearound.

6. A transportable cable-laying and recovery device, comprising a rotatable cable-storage drum, coacting rolls for feeding out cable unwound from said drum, a belt pulley connected to one of said rolls, a belt engaged by said pulley and mounted partly around the coil of cable upon said drum, a pivotal support for said drum, said support being movable away from said rolls by the weight of said drum so as to maintain tension of said belt during the unwinding of cable from said coil, and means for rotating either of said drum and said roll, the other of said drum and said roll being rotated simultaneously through the agency of said belt and pulley, and the speed-relation of said drum and said roll varying with the diameter of said coil having said belt mounted partly therearound.

IRWIN TREVANION KEMPE.
